(57) **CLAIM**

The ornamental design for a joint pad with stitching pattern, as shown and described.

DESCRIPTION

FIG. 1 is a perspective view of a joint pad with stitching pattern of our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of the back of the joint pad and straps are included for the purpose of illustrating structural environment and forms no part of the claimed design.
